ABSTRACT OF THE DISCLOSURE

Phenylphosphonium salts of this invention possess useful gastric antisecretory, spasmolytic and antiulcerogenic properties. A method of treating gastrointestinal hyperacidity and ulceration has also been disclosed.

CROSS REFERENCE TO RELATED APPLICATIONS

This is a division, of application Ser. No. 109,020, filed Jan. 22, 1972, now U.S. Pat. 3,755,459.

SUMMARY OF THE INVENTION

This invention describes new phosphonium salts and processes for their preparation. This invention further provides valuable pharmaceutical preparations which contain these phosphonium salts as gastric antisecretory, spasmolytic, and antiulcerogenic agents. A method for the treatment of gastrointestinal hyperacidity and ulceration is also described.

BACKGROUND OF THE INVENTION

The pharmaceutical compositions which have been used as antisecretory and spasmolytic agents have been such as atropine, homatropine, propantheline bromide, dicyclomine hydrochloride and other compounds which are structurally dissimilar to the onium salts of this invention. Due to the anticholinergic properties of these known compounds, they produce undesirable side effects such as mydriasis, xerostomia, cycloplegia, and other unwanted effects.

There have been a number of aryl phosphonium salts described in the literature. These have mainly been proposed for use as bactericidal and fungicidal agents, as well as plant growth regulators.

We have unexpectedly found novel phosphonium salts which have valuable pharmacologic properties.

We have found phosphonium salts which possess useful gastric antisecretory, spasmolytic and antiulcerogenic properties.

We have further found that the compounds of this invention are substantially void of the anticholinergic side effects which accompany heretofore known gastric antisecretory and spasmolytic agents.

We have also found a simple and effective method for treating gastric hyperacidity and gastrointestinal ulceration such as duodenal and peptic ulcers.

DESCRIPTION AND PREFERRED EMBODIMENTS

This invention provides a method of preparing novel phosphonium salts.

This invention further provides pharmacologically active chemical compounds which are useful in treating gastrointestinal hyperacidity and ulceration.

The compounds of this invention which are useful in treating gastrointestinal hyperacidity and ulceration may be described by the general Formula I:

2

where:

Ar is an aryl or substituted aryl group; R, R' and R'' may be the same or different and are a saturated or unsaturated acyclic member having up to 12 carbon atoms, or a saturated or partially unsaturated carbocyclic member having up to 12 carbon atoms; and A⁻ is a nontoxic inorganic or organic anion.

More specifically, the compounds of this invention may be described by the structural Formula II:

where:

X and Y may be the same or different and are hydrogen, loweralkyl, halo, haloloweralkyl, nitro, loweralkoxy, haloloweralkoxy, phenoxy, halophenoxy, phenyl or halophenyl;

R, R' and R'' may be the same or different and are a 5 to 12 carbon atoms member which may be straight chained or branched and are: alkyl, alkenyl, cycloalkyl, cycloalkenyl or cycloalkyloweralkyl;

R may also be loweralkyl, loweralkenyl, loweralkynyl, alkynyl, cycloalkenylloweralkyl, cycloloweralkyl, cycloloweralkylloweralkyl, arloweralkyl, polyfluoroloweralkyl, polyfluoroalkyl or substituted benzyl of the formula

where:

R_α is hydrogen or loweralkyl;

R₂, R₃, R₄, R₅ and R₆ may be the same or different and are hydrogen, halo, cyano, haloloweralkyl, nitro, haloloweralkoxy, haloloweracyl, haloloweralkylsulfonyl or halodiloweralkylsulfonamido; and

A⁻ is a pharmaceutically acceptable nontoxic inorganic or organic anion (preferably chloride, bromide, iodide, sulfate, hydrogen sulfate, nitrate, phosphate, dihydrogenphosphate, monohydrogenphosphate, acetate, maleate, citrate, benzoate, lactate, benzenesulfonate, methanesulfonate, ethanesulfonate, etc.).

The more preferred compounds of this invention are also the more preferred compounds which are useful in treating gastrointestinal disorders and diseases and are described by the structural Formula II:

where:

X and Y are hydrogen, halo, haloloweralkyl, nitro or haloloweralkoxy;

R, R' and R'' are a 5 to 12 carbon atom member which may be straight chained or branched and are alkyl or cycloalkyl;

R may also be arloweralkyl or substituted benzyl of the formula

where:

R_α is hydrogen or lower alkyl;

R₂, R₃, R₄, R₅ and R₆ are hydrogen, halo, haloloweralkyl, nitro or haloloweralkoxy; and

A⁻ is chloride, bromide, iodide, nitrate, phosphate or sulfate.

The most preferred compounds of this invention embrace those compounds of structural Formula II where:

X and Y are hydrogen, fluoro, chloro, bromo, trifluoromethyl, nitro or trifluoromethoxy;
R, R' and R'' are amyl, hexyl, heptyl, octyl, cycloamyl, cyclohexyl, cycloheptyl or cyclooctyl;
R may also be benzyl or substituted benzyl of the formula

where:

R_α is hydrogen or methyl; and
R₂, R₃, R₄, R₅ and R₆ are hydrogen, fluoro, chloro, bromo, trifluoromethyl, nitro or trifluoromethoxy; and
A⁻ is chloride, bromide or iodide.

A further more preferred embodiment of this invention embraces those compounds of Formula II where:

X and Y are hydrogen, halo, haloloweralkyl, nitro or haloloweralkoxy;
R' and R'' are a 5 to 12 carbon atom member which may be straight chained or branched and are: alkyl or cycloalkyl;
R is loweralkyl, loweralkenyl, loweralkynyl, cycloloweralkyl or cycloloweralkylloweralkyl;
A⁻ is chloride, bromide, iodide, nitrate, phosphate or sulfate.

The more preferred compounds of this latter embodiment are exemplified where:

X and Y are hydrogen, fluoro, chloro, bromo, trifluoromethyl, nitro or trifluoromethoxy;
R' and R'' are amyl, hexyl, heptyl, octyl, cycloamyl, cyclohexyl, cycloheptyl or cyclooctyl;
R is loweralkyl, loweralkenyl, loweralkynyl, cycloloweralkyl or cycloloweralkylloweralkyl;
A⁻ is chloride, bromide or iodide.

In the descriptive portions of this invention, the following definitions apply: The term "lower alkyl" refers to a lower alkyl hydrocarbon group containing from 1 to 5 carbon atoms which may be straight chained or branched.

The "lower alkoxy" radical signifies an alkoxy group containing from 1 to 5 carbon atoms which can be straight chained or branched.

The compounds of this invention can contain an asymmetric phosphorous atom when R¹ ≠ R² ≠ R³ ≠ Ar. For this reason, they may be obtained as racemic mixtures or as dextro (+) and levorotatory (-) isomers. These may be separated by any of the various methods of resolution to obtain the d or l compound. These isomers may also be obtained via stereospecific condensation reactions. It is understood that the optical isomers of these compounds are embraced within the scope of this invention.

Representative compounds of this invention which are particularly useful are as follows:

trioctylphenylphosphonium chloride
trioctyl(p-fluorophenyl) phosphonium chloride
trioctyl(p-trifluoromethyl) phosphonium chloride
dioctylbenzylphenylphosphonium chloride
dioctyl(p-fluorobenzyl) phenylphosphonium chloride
dioctyl(p-trifluoromethylbenzyl) phenylphosphonium chloride
dioctylamylphenylphosphonium chloride
dihexylamylphenylphosphonium chloride
dioctyl(p-bromobenzyl) phenylphosphonium bromide
dioctyl(2,3,4,5,6-pentafluorobenzyl) phenylphosphonium chloride
triheptylphenylphosphonium chloride
trihexylphenylphosphonium chloride

tricyclohexylphenylphosphonium chloride
tricycloheptylphenylphosphonium chloride
diheptyl(2,6-dichlorobenzyl) phenylphosphonium chloride
dioctyl(2,6-dichlorobenzyl) (p-chlorophenyl) phosphonium chloride
dihexyl(α-methylbenzyl) (p-chlorophenyl) phosphonium chloride
dihexylmethylphenylphosphonium chloride
dihexylethylphenylphosphonium chloride
10 dihexylpropylphenylphosphonium chloride
dihexyl(i-propyl) phenylphosphonium chloride
dihexylbutylphenylphosphonium chloride
dihexyl(i-butyl) phenylphosphonium chloride
dihexyl(s-butyl) phenylphosphonium chloride
15 dihexyl(t-butyl) phenylphosphonium chloride
dihexylpentylphenylphosphonium chloride
dihexyloctylphenylphosphonium chloride
dihexylallylphenylphosphonium chloride
dihexylmethylallylphenylphosphonium chloride
20 dihexyl(2-butenyl) phenylphosphonium chloride
dihexyl(3-butenyl) phenylphosphonium chloride
dihexyl(4-pentenyl) phenylphosphonium chloride
dihexyl(2,4-pentadienyl) phenylphosphonium chloride
dihexyl(2-propenyl) phenylphosphonium chloride
25 dihexylcyclopropylphenylphosphonium chloride
dihexylcyclopropylmethylphenylphosphonium chloride
dihexylcyclopropylethylphenylphosphonium chloride
dihexylcyclobutylphenylphosphonium chloride
dihexylcyclobutylmethylphenylphosphonium chloride
30 dihexylcyclopentylphenylphosphonium chloride
dihexyl(2-cyclopentenyl) phenylphosphonium chloride
dihexylpropargylphenylphosphonium bromide
dihexyl(2-cyclohexenyl) phenylphosphonium chloride
dihexylperfluorobutylphenylphosphonium chloride
35 dipentylallylphenylphosphonium chloride
diheptylallylphenylphosphonium chloride
dicyclohexylallylphenylphosphonium chloride
dicycloheptylallylphenylphosphonium chloride
dicyclooctylallylphenylphosphonium chloride
40 hexyloctylallylphenylphosphonium chloride
heptyloctylallylphenylphosphonium chloride
cyclohexyloctylallylphenylphosphonium chloride
cycloheptyloctylallylphenylphosphonium chloride
cyclooctyloctylallylphenylphosphonium chloride
45 tri-octyl(o-chlorophenyl) phosphonium chloride
trihexyl(m-chlorophenyl) phosphonium chloride
trihexyl(p-chlorophenyl) phosphonium chloride
trihexyl(2,3-dichlorophenyl) phosphonium chloride
trihexyl(2,4-dichlorophenyl) phosphonium chloride
50 trihexyl(2,5-dichlorophenyl) phosphonium chloride
trihexyl(2,6-dichlorophenyl) phosphonium chloride
trihexyl(3,4-dichlorophenyl) phosphonium chloride
trihexyl(3,5-dichlorophenyl) phosphonium chloride
trihexyl(2-bromophenyl) phosphonium chloride
55 trihexyl(3-bromophenyl) phosphonium chloride
trihexyl(4-bromophenyl) phosphonium chloride
trihexyl(4-trifluoromethylphenyl) phosphonium chloride
trihexyl(4-nitrophenyl) phosphonium chloride
trihexyl(4-methoxyphenyl) phosphonium chloride
60 dihexyl(o-chlorobenzyl) phenyl phosphonium chloride
dihexyl(m-chlorobenzyl) phenyl phosphonium chloride
dihexyl(p-chlorobenzyl) phenyl phosphonium chloride
dihexyl(2,3-dichlorobenzyl) phenyl phosphonium chloride
dihexyl(2,4-dichlorobenzyl) phenyl phosphonium chloride
65 dihexyl(2,5-dichlorobenzyl) phenyl phosphonium chloride
dihexyl(2,6-dichlorobenzyl) phenyl phosphonium chloride
dihexyl(3,4-dichlorobenzyl) phenyl phosphonium chloride
dihexyl(3,5-dichlorobenzyl) phenyl phosphonium chloride
dihexyl(2,3,4-trichlorobenzyl) phenyl phosphonium chloride
70 chloride
dihexyl(2,3,5-trichlorobenzyl) phenyl phosphonium chloride
dihexyl(2,3,6-trichlorobenzyl) phenyl phosphonium chloride
75 chloride

dihexyl(2,4,5-trichlorobenzyl)phenyl phosphonium chloride
 dihexyl(2,4,6-trichlorobenzyl)phenyl phosphonium chloride
 dihexyl(3,4,5-trichlorobenzyl)phenyl phosphonium chloride
 tripentylphenylphosphonium chloride
 trioctylphenylphosphonium chloride
 triisoamylphenylphosphonium chloride
 tricyclopentylphenylphosphonium chloride
 dipentylhexylphenylphosphonium chloride
 dipentylheptylphenylphosphonium chloride
 dipentylcyclohexylphenylphosphonium chloride
 diisoamylhexylphenylphosphonium chloride
 dipentylphenylbenzylphosphonium chloride
 diisoamylphenylbenzylphosphonium chloride.

The compounds of this invention may be prepared by the following general procedures:

Condensation of phosphorous trichloride with a molar amount of phenyl organometallic compound results in the phenyl dichlorophosphine. Further condensation with the proper organometallic reagents results in the trisubstituted phosphine. Reaction of the trisubstituted phosphine with the desired alkyl or aralkyl halide results in the corresponding quaternary phosphonium halide. [Phenyldichlorophosphines may also be prepared by the Michaelis modification of the Friedel-Crafts reaction as outlined in JACS 73:755-6 (1951).]

The following reaction equation illustrates this method of synthesis:

where X' is chloride, bromide or iodide. When X or Y is chloro, then X' is bromo or iodo but when X or Y is bromo, then X' is iodo.

Phosphonium compounds having two similar groups are prepared by reacting the phenyldichlorophosphine with two moles of Grignard reagent followed by condensation with the desired halide.

The above reactions may be carried out by the usual substitution process for reactions involving organometallic reagents with halogen derivatives of trivalent phosphorous compounds.

One such method is by carrying out the reaction with one, two or three moles of the desired organometallic reagent (preferably a Grignard reagent) in an inert medium such as ether, tetrahydrofuran, etc., and with increased temperatures. Isolation may be carried out either by subjecting the reaction mixture to vacuum distillation or by giving the mixture a hydrolytic treatment with am-

moniac chloride solution, followed by distillation of the organic layer.

Preparation of the phosphonium salts is preferably carried out with the phenyldisubstituted phosphine and a halide of the formula RX' where R and X' are as described above. The reaction is preferably carried out using a solvent and with increased temperatures. These reactions are also preferably carried out in an inert atmosphere under nitrogen or carbon dioxide. The solvent used should be one that is miscible with the reactants and after it is convenient to use the reactant halide in excess as the solvent or alternatively a high boiling polar medium such as phenol, acetonitrile, dimethylformamide, dimethylsulfoxide, methylethylketone, etc. The reaction temperature may vary from room temperature with readily reactive reactants to about 250° C., although it is preferable to run the reaction at temperatures from about 50° C. to 150° C. The isolation of the desired phosphonium halide can be carried out by distilling off the solvent in vacuo and precipitating the phosphonium halide by the addition of a hydrocarbon liquid such as n-pentane, n-hexane, cyclohexane, etc.

Other anion salts can be produced by exchange of the halide with alkali or alkaline earth salts containing the appropriate anion.

When R is substituted benzyl, it is preferable to prepare the phosphonium compound on the phenyldisubstituted phosphine with the desired benzyl halide.

This reaction is conveniently carried out on the benzyl bromide or chloride using a solvent and increased temperatures. This synthesis is carried out and isolated as described above.

The benzyl halide starting materials can be conveniently prepared by the following reactions.

Diazotization of an aromatic amine in the conventional manner followed by a Sandmeyer (a) type displacement produces the nitrile, which is then hydrolyzed (b) to the carboxylic acid. Rosenmund reduction (c) of the carboxylic acid results in the aldehyde which in turn is interacted with the desired alkyl Grignard reagent and oxidized (d) to obtain the α -alkylketone. This may then be reduced catalytically (e) to the α -alkylbenzyl alcohol. The alcohol is treated with a phosphorous trihalide, phosphorous oxyhalide, phosphorous pentahalide, thionylhalide or sulfonyl halide reagent (f) to obtain the α -alkylbenzyl halide. Lithium aluminum hydride reduction of the benzoic acid (g) results in the benzyl alcohol which is then treated as above (f) to obtain the benzyl halide.

The phenyl Grignard reagents may be prepared from the corresponding aniline by conventional diazotization followed by a Sandmeyer type reaction using cuprous bromide or cuprous iodide to obtain the desired phenyl halide which is then converted to the Grignard.

Appropriately desired end products having various X, Y, R₂, R₃, R₄, R₅ and R₆ substituents can be prepared at various stages of the synthesis of the starting materials by using suitable reactions in order to convert one group to another. Thus, for example, using conventional methods, a halogen group can be treated under Rosenmund von Brown conditions to the nitrile compound which in turn can be hydrolyzed to a carboxy. A nitro can be reduced to an amino which can be alkylated to the dialkylamino substituent. A hydroxy compound can be prepared by demethylation of a methoxy substituent. A Sandmeyer type reaction can be carried out on an amino compound to introduce a chloro, bromo, xanthate, hydroxyl or alkoxyl group. The xanthate can then lead to the mercapto by hydrolysis, this turn can be alkylated to an alkylthio group which can be oxidized to alkylsulfinyl and alkylsulfonyl groups.

We have found that the compounds of this invention have useful antiulcerogenic properties. Further, they have an effective degree of gastric anti-secretory activity, i.e., they reduce the volume and the acidity of the gastric fluid in humans and mammals. Still further, these compounds produce a considerable spasmolytic action on the gastrointestinal musculature, i.e., they reduce the peristaltic action of the gastrointestinal musculature which is manifested by a delay in gastric emptying time.

Until now, the known antiulcerogenic compounds which showed gastric anti-secretory and gastrointestinal spasmolytic action have included such agents as atropine, homatropine, propantheline, dicyclomine, etc. These compounds, however, cause accompanying undesirable anticholinergic properties such as mydriasis, xerostomia, cycloplegia, etc.

We have found that the phosphonium compounds of this invention are particularly useful as antisecretory, anti-spasmodic and antiulcerogenic agents because they are essentially devoid of these unwanted effects.

In particular, the phosphonium compounds, as herein described, are useful in the treatment of such gastrointestinal disorders and diseases as duodenal ulcer and peptic ulcer.

For all these purposes, the phosphonium compounds of this invention can be administered orally or parenterally, but they are preferably administered orally. Orally, they may be administered as tablets, aqueous or oily suspension, dispersible powders or granules, emulsions, hard or soft capsules, or syrups or elixirs. The term parenteral,

as used herein, includes subcutaneous injection, intramuscular injection or infusion techniques.

Compositions intended for oral use may be prepared according to any method known to the art for the manufacture of pharmaceutical compositions and such compositions may contain one or more agents selected from the group consisting of sweetening agents, flavoring agents, coloring agents and preserving agents, in order to provide a pharmaceutically elegant and palatable preparation.

Further, these compounds may be tableted or otherwise formulated so that for every 100 parts by weight of the composition, there are present between 5 and 95 parts by weight of the active ingredient. The dosage unit form will generally contain between about 1 mg. and about 500 mg. of the active ingredients of this invention. The preferred unit dose is between about 10 mg. and 100 mg.

The dosage regimen in carrying out the methods of this invention is that which insures maximum therapeutic response until improvement is obtained and thereafter the minimum effective level which gives relief. Thus, in general, the dosages are those that are therapeutically effective in the treatment of ulcerogenic disease conditions or symptoms, such as duodenal and peptic ulcer. In general, the daily dose can be between about 0.1 mg./kg. and 50 mg./kg. (preferably in the range of 1-25 mg./kg./day). Bearing in mind, of course, that in selecting the appropriate dosage in any specific case, consideration must be given to the patient's weight, general health, age and other factors which may influence response to the drug.

Various tests in animals have been carried out to show the ability of the compounds of this invention to exhibit reactions that can be correlated with antiulcerogenic activity in humans. These tests involve such as the effects of the phosphonium compounds on gastric secretion, gastrointestinal spasm and their effect against ulcerogenic agents. It has been found that the compounds of this invention when tested in the above variety of situations show a marked activity.

One such test is the gastric secretion test. This test is carried out as follows: Shay rats are fasted for 4-8 hours, and water is given ad lib. The rats are selected at random and separated into groups of 10. The animals are treated intraduodenally (I.D.) with the test compound or the vehicle immediately subsequent to the ligation of the stomach at the pyloric sphincter. The animals are sacrificed with chloroform at 4 hours post-drug administration, the stomach is removed and its contents are assayed for volume, pH and total acids.

A second gastric secretion test is carried out on dogs. This is outlined in the Handbook of Physiology, Section 6: Alimentary Canal, vol. II: Secretion, American Physiology Society, Washington, D.C., 1967.

It has been found that the compounds of this invention when subjected to the above gastric secretion tests display a marked ability to decrease gastric volume and gastric acidity. These tests are known to correlate well with gastric activity in humans and is a standard test used to determine anti-secretory properties.

To determine the antiulcer effectiveness, the following test is employed: Male Wistar rats (130-150 grams) are fasted for 24 hours, then given reserpine at 5 mg./kg. i.p. Twenty-four hours later, the stomachs are removed and examined for ulceration. Ulcers are graded on a 0-4 scale and the number of ulcers is recorded. Pretreatment with the phosphonium compounds of this invention produces a decrease in ulcer grade and the number of ulcers compared to the control reserpine-treated rats.

Determination of anti-spasmodic properties can be carried out by the procedure as outlined by D. A. Brodie and S. K. Kundrats in their article entitled "Effect of Drugs on Gastric Emptying in Rats," Fed. Proc. 24:714 (1965).

Mydriasis is detected by the procedure R. A. Turner, Screening Methods in Pharmacology, Academic Press, New York, and London, pp. 174-5, 1965. Acute toxicity

is calculated according to the standard Litchfield-Wilcoxon procedure.

In view of the results of these tests, the pharmacological data clearly indicates that the phosphonium compounds of this invention can be considered to be effective antiulcerogenic, antisecretory, and antispasmodic agents which are substantially free of anticholinergic side effects and having a low toxicity.

The following are detailed examples which show the preparation of the compounds of this invention. They are to be construed as illustrations of said compounds and not as limitations thereof.

EXAMPLE 1

Phenylchlorophosphine

To 83 g. (0.6 mole) of phosphorus trichloride is added 27 g. (0.2 mole) of aluminum chloride and 13.8 g. (0.15 mole) of dry benzene. This reaction mixture is then gently heated for 2 hours with stirring over a blanket of nitrogen to expell the formed hydrogen chloride. The reaction mixture is then refluxed with vigorous stirring for an additional hour. The heat source is then removed and while the reaction mixture is still hot, phosphorus oxychloride 30.7 g. (0.2 mole) is gradually added. The mixture is then allowed to cool to room temperature and extracted continuously with petroleum ether for 2 hours. The petroleum ether extract is then concentrated in vacuo and distilled to obtain phenylchlorophosphine.

When benzene in the above example is replaced by the compounds of Table I below and the reaction product is fractionated then the corresponding product of Table II below is prepared.

TABLE I

Toluene
Ethylbenzene
Propylbenzene
i-Propylbenzene
t-Butylbenzene
o-Xylene
m-Xylene
p-Xylene
Biphenyl
p-Methylbiphenyl

(p,p'-Methylbiphenyl)dichlorophosphine
p-Methoxyphenylchlorophosphine
p-Ethoxyphenylchlorophosphine
2,4-dimethoxyphenylchlorophosphine
p-Trifluoromethoxyphenylchlorophosphine
p-Phenoxyphenylchlorophosphine
3,4-diethylphenylchlorophosphine.

EXAMPLE 2

Diethylphenylphosphine

To a Grignard mixture of n-octylmagnesium chloride (0.53 mole) prepared from 13.8 g. of magnesium turnings and 78.4 g. of n-octyl chloride in 1300 ml. ether is added 31.2 g. (0.175 mole) of phenylchlorophosphine in 100

ml. of ether with vigorous stirring and in a nitrogen atmosphere at 0° C. The reaction mixture is allowed to warm to room temperature over 2 hours. The mixture is then poured onto an ice-cold saturated solution of ammonium chloride (250 ml.) and the mixture stirred for an additional hour. The aqueous layer is extracted with 2-150 ml. portions of ether which is then combined with the ether layer, dried over sodium sulfate, evaporated to dryness and distilled to obtain diethylphenylphosphine.

When n-octyl chloride in the above reaction is substituted with the halides of Table I below, then the corresponding product of Table II below is prepared.

TABLE I

15 n-Pentyl chloride
n-Hexyl chloride
n-Heptyl chloride

EXAMPLE 6

Dihexylphenylphosphine

To a Grignard mixture of n-hexylmagnesium chloride (0.45 mole) prepared from 11.8 g. of magnesium turnings and 54 of n-hexylchloride in 1 l. ether is added 31.2 g. (0.175 mole) of phenyldichlorophosphine in 100 ml. of ether with vigorous stirring and in a nitrogen atmosphere at 0° C. The reaction mixture is allowed to warm to room temperature for 3 hours. The mixture is poured onto a saturated ice-bath solution of ammonium chloride and the mixture stirred for an additional half hour. The mixture is extracted three times with 300 ml. portions of ether. The ether is dried over sodium sulfate, evaporated to dryness and fractionated to obtain dihexylphenylphosphine.

When phenyldichlorophosphine in the above example is replaced by the phenylphosphine of Table II, Example 5, then the corresponding product of Table I below is prepared.

TABLE I

Dihexyl(2-chlorophenyl)phosphine
Dihexyl(3-chlorophenyl)phosphine
Dihexyl(4-chlorophenyl)phosphine

Dihexyl(3-methoxyphenyl)phosphine
Dihexyl(4-methoxyphenyl)phosphine
Dihexyl(2,4-dichlorophenyl)phosphine
Dihexyl(2,6-dichlorophenyl)phosphine.

EXAMPLE 7

Hexylphenylchlorophosphine

To a Grignard mixture of hexylmagnesium chloride (0.1 mole) prepared from (2.6 g. of magnesium turnings and 16.3 g. of hexylbromide in 300 ml. of ether) is added dropwise to an inert atmosphere with stirring and at 0° C., 43 g. (0.15 mole) of phenyldichlorophosphine in 75 ml. of ether. The reaction mixture is stirred over 1/2 hours and allowed to gradually warm to room temperature. The reaction mixture is then filtered, residue washed with ether combined with the filtrate and concentrated in vacuo and distilled to obtain hexylphenylchlorophosphine.

14

When hexylbromide in the above reaction is replaced with the halides of Example 2, then the corresponding phosphine of Table I, below is prepared.

Cyclohexyl(3,5-dichlorophenyl)chlorophosphine
Cycloheptyl(2-methoxyphenyl)chlorophosphine
Decyl(3-methoxyphenyl)chlorophosphine
Cyclohexyl(3-bromophenyl)chlorophosphine
Cyclohexyl(3-chlorophenyl)chlorophosphine
(Cyclohex-2-enyl) (4-methoxyphenyl)chlorophosphine
(Iso-octenyl) (4-phenoxyphenyl)chlorophosphine
Pentyl(4-trifluoromethylphenyl)chlorophosphine
Cyclohexylmethyl(4-bromophenyl)chlorophosphine
(2-ethylhexyl) (4-t-butylphenyl)chlorophosphine
(Cyclooct-2-enyl) (4-ethoxyphenyl)chlorophosphine
Cycloheptyl(4-fluorophenyl)chlorophosphine
onyl(4-i-propylphenyl)chlorophosphine
(2-methylheptyl) (4-nitrophenyl)chlorophosphine
cyclopentyl(4-chlorophenyl)chlorophosphine
(3-methylheptyl) (2,3-dimethylphenyl)chlorophosphine
Isoamyl(2,3-dichlorophenyl)chlorophosphine
(4-methyl-3-penten-1-yl) (4-trifluoromethoxyphenyl)
chlorophosphine
Undecyl(4-methylphenyl)chlorophosphine
Isoamyl(3,4-diethylphenyl)chlorophosphine
Cyclohexyl(2,4-dimethylphenyl)chlorophosphine
(2,2,3,3-tetramethylbutyl) (4-phenoxyphenyl)chloro-
phosphine
(2-propylallyl) (4-biphenyl)chlorophosphine
Cyclohexyl(3,4-dichlorophenyl)chlorophosphine
Cyclohexylmethyl(2,4-diethylphenyl)chlorophosphine
Isoamyl(2,5-dimethylphenyl)chlorophosphine
Cyclopentyl(2,4-dimethylphenyl)chlorophosphine
Dodecyl(2-methyl-5-i-propylphenyl)chlorophosphine
Isoamyl(p-propylphenyl)chlorophosphine
Pentyl(2,6-dichlorophenyl)chlorophosphine
Cyclohexyl(2,4-dichlorophenyl)chlorophosphine
(3,4,5-trimethylheptyl) (3,4-dinitrophenyl)chloro-
phosphine
Cyclohexyl(4,4'-chlorobiphenyl)chlorophosphine.

EXAMPLE 10

Hexyloctylphenylphosphine

To a Grignard mixture of octylmagnesium bromide (0.075 mole) in 250 ml. of ether is added dropwise with stirring 28.5 g. (0.125 mole) of hexylphenylchlorophosphine in 75 ml. of ether at 0° C. The reaction is carried out under nitrogen and vigorously stirred for 2 hours. The temperature is allowed to gradually warm up to room temperature. The reaction mixture is then poured onto an ice-cold saturated solution of ammonium chloride (300 ml.) and the mixture stirred for one hour. The aqueous layer is extracted with 200 ml. of ether combined with the ether layer, dried over sodium sulfate, evaporated to dryness and distilled to give hexyloctylphenylphosphine.

When the octylmagnesium bromide of the above reaction is replaced with the Grignard reagents of the halides of Table I, Example 2, then the corresponding tertiary phosphine of Table I below is prepared.

Pentylhexylphenylphosphine
Dihexylphenylphosphine
Heptylhexylphenylphosphine
Nonylhexylphenylphosphine

16

5 Decylhexylphenylphosphine
Undecylhexylphenylphosphine
Dodecylhexylphenylphosphine
Isoamylhexylphenylphosphine
(2-methyl-1-butene)hexylphenylphosphine
(Cyclohex-2-enyl)hexylphenylphosphine
Cyclooctylhexylphenylphosphine
Cycloheptylhexylphenylphosphine
Cyclopentylphenylphosphine
10 Cyclohexylhexylphenylphosphine
Cyclohexylmethylhexylphenylphosphine
(3,4,5-trimethylheptyl)hexylphenylphosphine
(2-propylallyl)hexylphenylphosphine
(4-methyl-3-penten-1-yl)hexylphenylphosphine
15 (2-methylheptyl)hexylphenylphosphine
(3-methylheptyl)hexylphenylphosphine
(2-ethylhexyl)hexylphenylphosphine
(2,2,3,3-tetramethylbutyl)hexylphenylphosphine
(Cyclooct-2-enyl)hexylphenylphosphine
20 Iso-octenylhexylphenylphosphine.

EXAMPLE 11

When hexylphenylchlorophosphine of Example 10 is replaced by the chlorophosphines of Table I, Example 7, then the corresponding tertiary phosphine of Table I below is prepared.

TABLE I

Octylpentylphenylphosphine
30 Octylheptylphenylphosphine
Diethylphenylphosphine
Octylisopropylphenylphosphine
Octyldecylphenylphosphine
Octylundecylphenylphosphine
35 Octylidodecylphenylphosphine
Octylisoamylphenylphosphine
Octyl(2-methyl-1-butene)phenylphosphine
Octyl(cyclohex-2-enyl)phenylphosphine
Octylcyclooctylphenylphosphine
40 Octylcycloheptylphenylphosphine
Octylcyclopentylphenylphosphine
Octylcyclohexylphenylphosphine
Octylcyclohexylmethylphenylphosphine
Octyl(3,4,5-trimethylheptyl)phenylphosphine
45 Octyl(2-propylallyl)phenylphosphine
Octyl(4-methyl-3-penten-1-yl)phenylphosphine
Octyl(2-methylheptyl)phenylphosphine
Octyl(3-methylheptyl)phenylphosphine
Octyl(2,2,3,3-tetramethylbutyl)phenylphosphine
50 Octyl(cyclooct-2-enyl)phenylphosphine
Octyl(iso-octenyl)phenylphosphine.

EXAMPLE 12

When hexylphenylphosphine of Example 10 is replaced by the chlorophosphines of Table I, Example 8, then the corresponding tertiary phosphine of Table I, below is prepared.

TABLE I

 phosphine
 40 Cyclohexyl(4,4'-chlorobiphenyl)isoamylphosphine.

EXAMPLE 14

Hexyloctylpentylphenylphosphonium chloride

45 To 76.5 g. (0.25 mole) of hexyloctylphenylphosphine in 500 ml. of acetonitrile is added 28.6 g. (0.27 mole) of pentyl chloride. The mixture is refluxed for 15 hours, concentrated in vacuo and the residue agitated with 3-200 ml. portions of hexane. The hexane is evaporated to give hexyloctylpentylphenylphosphonium chloride.

50 When the procedure is followed but pentyl chloride is substituted for the halides of Table I below, then the corresponding product is prepared.

TABLE I

55 Methyl iodide
 Ethyl bromide
 Propyl bromide
 i-Propyl bromide
 Butyl bromide
 60 i-Butyl chloride
 Sec-butyl chloride
 t-Butyl bromide
 Allyl bromide
 Methallyl chloride

EXAMPLE 16

Dihexyl (p-trifluoromethylbenzyl)phenylphosphonium chloride

To 10.7 g. (0.04 mole) of dihexylphenylphosphine suspended in 100 ml. of acetonitrile is added 9.7 g. (0.05 mole) of p-trifluoromethylbenzyl chloride in 75 ml. of acetonitrile. The reaction mixture is then heated at reflux for 24 hours, cooled and evaporated to dryness in vacuo. The residue is dissolved in hexane:ether, treated with charcoal, filtered and concentrated to dryness in vacuo

23

to obtain dihexyl(p-trifluoromethylbenzyl)phenylphosphonium chloride.

When p-trifluoromethylbenzyl chloride in the above example is substituted by the benzyl halides of Table I below, then the corresponding product is prepared.

EXAMPLE 18

Dihexyloctylphenylphosphonium bromide

26 g. of dihexyloctylphenylphosphonium chloride is added to 200 ml. of a saturated aqueous sodium bromide solution. The mixture is then heated to 90°, the solid is melted and the mixture is stirred for 5 min., cooled in an ice-bath and the water decanted. Another 200 ml. of saturated sodium bromide solution is added and the procedure repeated. The ion exchanged phosphonium bromide is filtered, washed with 1 liter of water followed by 2–200 ml. portions of hexane. The product is then heated twice with 300 ml. of distilled water until a melt, cooled and the water decanted, triturated with hexane, and dried to obtain dihexyloctylphenylphosphonium bromide.

When the sodium bromide solution of the above example is replaced with a solution of an appropriate salt of Table I below, then the corresponding desired phosphonium salt of Table II below is obtained.

TABLE I

Sodium iodide	Potassium oxalate
Sodium sulfate	Potassium bromide
Sodium nitrate	Sodium phosphate
Sodium maleate	Lithium bromide
Sodium citrate	Sodium benzoate
Sodium acetate	Sodium methanesulfonate

TABLE II

Dihexyloctylphenylphosphonium iodide
Dihexyloctylphenylphosphonium sulfate
Dihexyloctylphenylphosphonium nitrate
Dihexyloctylphenylphosphonium maleate
Dihexyloctylphenylphosphonium citrate
Dihexyloctylphenylphosphonium acetate
Dihexyloctylphenylphosphonium oxalate
Dihexyloctylphenylphosphonium bromide
Dihexyloctylphenylphosphonium phosphate
Dihexyloctylphenylphosphonium bromide
Dihexyloctylphenylphosphonium benzoate
Dihexyloctylphenylphosphonium methanesulfonate

When the appropriate phosphonium salt is desired for any of the compounds of this invention, then the above procedure may be used.

We claim:

1. A method of treating gastrointestinal hyperacidity or ulceration in a human or mammal which comprises the oral or parenteral administration thereto of a

therapeutically effective amount of a compound of the formula:

where:

- X and Y are hydrogen, fluoro, chloro, bromo or trifluoromethyl;
 R, R' and R'' are amyl, hexyl, heptyl, cycloamyl, octyl, cyclohexyl, cycloheptyl or cyclooctyl;
 R may also be benzyl or substituted benzyl of the formula

where:

- 20 R₁ is hydrogen or methyl, R₂, R₃, R₄, R₅ and R₆ are hydrogen, fluoro, chloro or bromo;
 A⁻ is chloride, bromide or iodide.
 2. The method of claim 1 wherein the compound is tri-octylphenylphosphonium chloride.
 3. The method of claim 1 wherein the compound is tri-amylphenylphosphonium chloride.
 4. The method of claim 1 wherein the compound is tri-heptylphenylphosphonium chloride.
 5. The method of claim 1 wherein the compound is tri-cyclohexylphenylphosphonium chloride.
 6. The method of claim 1 wherein the compound is tri-cycloheptylphenylphosphonium chloride.
 7. A method of treating gastrointestinal hyperacidity or ulceration in a human or mammal which comprises the oral or parenteral administration thereto of a therapeutically effective amount of a compound of the formula:

where:

- X and Y are hydrogen, halo or haloloweralkyl;
 R and R'' are a 5 to 12 carbon atom member which may be straight chained or branched and are: alkyl or cycloalkyl;
 R is loweralkyl, loweralkenyl, loweralkynyl or cyclo-loweralkylloweralkyl;
 A⁻ is chloride, bromide, iodide, nitrate, phosphate or sulfate.
 8. The method of claim 7 where:
 X and Y are hydrogen, fluoro, chloro, bromo or trifluoromethyl;
 R and R'' are amyl, hexyl, heptyl, octyl, cycloamyl, cyclohexyl, cycloheptyl or cyclooctyl;
 R is a loweralkyl, loweralkenyl, loweralkynyl, cyclo-loweralkyl or cycloloweralkylloweralkyl;
 A⁻ is chloride, bromide or iodide.
